FIG. 5.

UNITED STATES PATENT OFFICE.

HENRY L. DAY, OF MINNEAPOLIS, MINNESOTA.

FUEL-FEEDER.

No. 821,930.

Specification of Letters Patent.

Patented May 29, 1906.

Application filed August 13, 1904. Serial No. 220,820.

To all whom it may concern:

Be it known that I, HENRY L. DAY, of Minneapolis, in the county of Hennepin, State of Minnesota, have invented certain new and 5 useful Improvements in Fuel-Feeders, of which the following is a specification.

This invention relates to improvements in devices designed for feeding finely-divided fuel into any suitable furnace; and the objects I have in view are to provide suitable means whereby the fuel may be evenly and regularly supplied to the mechanism by which it is delivered to the combustion-chamber of the furnace.

15 The invention consists generally in a suitable hopper or fuel-receptacle with a conveyer arranged therein and adapted to move the fuel toward a suitable exit-opening and other conveyers operating at substantially right angles to the first-named conveyer and serving to maintain the fuel in condition for being operated upon by the first-named conveyer.

20 The invention consists, further, in the constructions and combinations hereinafter described, and particularly pointed out in the claims.

25 In the accompanying drawings, forming part of this specification, Figure 1 is an elevation of a furnace-front, showing my fuel-feeder applied thereto. Fig. 2 is a side elevation of the feeder with a section of a portion of the furnace-front, showing the connection of the furnace-pipe therewith. Fig. 3 is a 30 plan view of a portion of the feeder. Fig. 4 is a vertical section of a portion of the fuel-hopper and the conductor leading to the fan. Fig. 5 is a transverse section on a plane at right angles to the plane of Fig. 4.

35 In Letters Patent of the United States issued to me April 26, 1898, No. 603,076, I have shown and described a fuel-feeder having means for producing a continuous air-current or air-belt with means for directing the 40 fuel into said air-current and means for separating the fuel from the air-current and directing it into a suitable furnace. The present invention is an improvement upon the fuel-feeder of my said former patent and relates particularly to the means for directing 45 the fuel into the air-current.

50 In the drawings, 2 represents a furnace of any suitable construction, and 3 the stack leading therefrom. Arranged in connection 55 with this furnace is an air-belt fuel-feeder of substantially the construction shown in my

former patent above referred to and comprising the fan or blower 5, the separator 6, the pipe or conductor 7, leading from the exit side of the fan to the inlet of the separator, 60 and the return-pipe 8, leading from the discharge side of the separator to the inlet of the fan. The fuel separated from the air-current by the separator 6 passes through a suitable pipe 9 to the combustion-chamber of the furnace. 65 These parts are of substantially the construction shown and described in my aforesaid patent. 10 represents a suitable hopper or receptacle, into which the fine material, such as shavings or fine coal-dust, is 70 placed and from which it is fed into the pipe or conductor 8, leading from the fuel-separator to the fan. This hopper may be of any suitable size and construction. It is preferably provided with one inclined side wall 11, 75 with the opposite vertical wall 12 and the vertical end walls 13. I do not limit myself, however, to any particular shape of hopper. At the bottom of the hopper I preferably provide a conveyer-trough 14, extending lengthwise of the hopper and having at one end an opening 15, which communicates with the interior of the pipe or conveyer 8. This opening is preferably provided with a slide-valve 16, by means of which the opening may be 80 wholly or partially closed. Arranged in the conveyer-trough 14 and mounted in suitable bearings in the end walls of the hopper is a spiral or screw conveyer 17. This conveyer is adapted to move material along in the conveyer-trough to the opening 15, through which it falls into the conductor 8, in which it is taken up by the air-current passing through said conductor to the fan. Arranged at one side 85 of the conveyer-trough and mounted in suitable bearings are the upright conveyers 18. These conveyers are preferably arranged in proximity to the vertical wall 12 of the hopper, and at their upper ends they are provided with the beveled gears 19, meshing with similar gears 20 upon a counter-shaft 21. The upright conveyers are preferably rotated, so as to tend to move the material upward in the hopper, and their purpose is to prevent the material from arching or bridging over from 90 one wall of the hopper to the other. 95

100 I have found that in feeding shavings or like material from the hopper by means of a screw conveyer or similar device there is a tendency for the material to arch or bridge over the conveyer. This will stop the feed of the material. To prevent this, I use the 105

upright conveyers and rotate them in a direction to move the material upward. This keeps the fine material in the vicinity of the conveyer always in motion and prevents its 5 arching or bridging over the conveyer. The counter-shaft 21 is mounted in suitable bearings 22, preferably supported upon suitable beams 23, forming a supporting-frame for the hopper and the feed mechanism.

10 I prefer to provide means by which the fan, the longitudinal conveyer, and the upright conveyers may all be driven from a single driving-shaft. As herein shown, 24 represents a suitable driving-shaft mounted in 15 bearings 25 upon the cross-beams 23 of the framework. This shaft is provided with a pulley 26, and the fan-shaft 27 is provided with a pulley 28. A belt 29 extends from the pulley 26 to the pulley 28, and by this 20 means the fan is continuously driven. This fan, as before stated, creates a circulation of air or an "air-belt," as it may be termed, from the fan-casing through the conductor 7, through the fuel-separator 6, and through 25 the conductor 8 back to the fan. The driving-shaft 24 is also provided with a pulley 30, and a counter-shaft 31 is provided with a pulley 32. A belt 33 extends from the pulley 30 upon the shaft 24 around the pulley 32, 30 and by this means the counter-shaft 31 is also driven. This shaft is provided with the pulley 34. A short shaft 35, mounted in bearings 36 upon the beams 23 of the framework, is provided with a pinion 37, that meshes with 35 a pinion 38 upon the shaft 21. The shaft 35 is provided with a pulley 39, and a belt 40 extends from the pulley 34 around the pulley 39. By this means the shaft 21 is driven and the upright conveyers 18 are all rotated.

40 It is desirable to provide means to rotate the conveyer 17 at any desired speed so as to regulate the feed of the fuel from the hopper into the conductor 8. For this purpose the shaft of the conveyer is provided with a gear 41, and a pinion 42, mounted upon a shaft 43, meshes with the gear 41. The shaft 43 is provided with a cone-pulley 44, and a similar cone-pulley 45 is arranged upon the shaft 31. A belt 46 passes around these two pulleys and may be shifted lengthwise thereof by hand or by any suitable means. By this means the conveyer 17 is driven, and the speed thereof may be regulated so as to regulate the feed of the material into the conductor 8. I do not limit myself to the details of the construction, as the same may be varied in many particulars without departing from my invention, nor do I limit myself to any particular location and arrangement of the 55 auxiliary conveyers which serve to keep the material in motion and prevent its arching or bridging over the main conveyer.

I claim as my invention—

1. The combination, in a fuel-feeder, with 65 a suitable hopper provided with a discharge-

opening, of a conveyer arranged in said hopper and adapted to move material to said discharge-opening, and a conveyer arranged in said hopper and operating to move a portion of the material away from said discharge-opening. 70

2. The combination, in a fuel-feeder with a suitable hopper provided with a discharge-opening, of a conveyer arranged in said hopper and adapted to move material to said 75 discharge-opening, and a series of conveyers arranged in said hopper and extending at an angle to said first-named conveyer and operating to move the material affected thereby away from said discharge-opening in the hopper in a loose condition. 80

3. The combination, in a fuel-feeder, with a suitable hopper provided with a discharge-opening, of a conveyer arranged in said hopper and adapted to move material to said 85 discharge-opening, and a series of conveyers arranged in said hopper and extending upward therein and operating to move the material affected thereby away from said discharge-opening. 90

4. The combination, in a fuel-feeder with a suitable hopper provided with a discharge-opening, of a conveyer arranged in said hopper and adapted to move material to said 95 discharge-opening, and a series of conveyers arranged in said hopper and extending substantially at a right angle to said first-named conveyer and operating to move the material affected thereby away from said discharge-opening. 100

5. The combination, in a fuel-feeder, with a suitable hopper provided with a discharge-opening, of a conveyer arranged in said hopper and serving to move material to said discharge-opening, a conveyer arranged in said 105 hopper and extending upward therein, and means for rotating said last-named conveyer so as to move the material upward in the hopper and prevent it from bridging above said hopper-opening, substantially as described. 110

6. The combination, in a fuel-feeder with a suitable hopper provided with a discharge-opening, of a conveyer arranged in said hopper and adapted to move material to said 115 discharge-opening, and a series of conveyers arranged in said hopper and extending upward therein, and means for rotating said last-named conveyers so as to move material upward in said hopper whereby the material 120 in the hopper may be maintained in a loose condition and prevented from bridging between the walls of said hopper.

7. The combination, in a fuel-feeder, with a hopper having a discharge-opening, of a 125 conveyer operating to move the material in said hopper to said discharge-opening, and a conveyer operating to prevent the material from bridging above said first-named conveyer, for the purpose specified. 130

8. The combination, in a fuel-feeder, with
a hopper having a discharge-opening, of a
conveyer operating to move the material to
said opening, and a series of conveyers ar-
5 ranged substantially parallel with one an-
other and operating close to a side wall of
said hopper to prevent the material from
bridging between the hopper-walls, substan-
tially as described.
- 10 9. The combination, in a fuel-feeder, with
a hopper having a discharge-opening, of a
conveyer operating to move the material to

said discharge-opening, and a series of con-
veyers operating close to a side wall of said
hopper to move the material affected there-
by upward and prevent the formation of
bridges between the hopper-walls, substan-
tially as described. 15

In witness whereof I have hereunto set my
hand this 10th day of August, 1904.

HENRY L. DAY.

In presence of—

A. C. PAUL,
C. G. HANSON.
